UNITED STATES PATENT OFFICE.

RAFFAELLO ASTARITA, OF NEW YORK, N. Y., ASSIGNOR TO SONDHEIM & MAGNUS, OF SAME PLACE.

DESIGN FOR A PILLOW-TOP.

SPECIFICATION forming part of Design No. 31,909, dated November 28, 1899.

Application filed October 31, 1899. Serial No. 735,429. Term of patent 3½ years.

To all whom it may concern:

Be it known that I, RAFFAELLO ASTARITA, a subject of the King of Italy, residing in the city of New York, borough of Manhattan, in 5 the county and State of New York, have invented and produced a new and original Design for a Pillow-Top, of which the following is a full, clear, and exact description.

Reference is to be had to the accompanying 10 drawing, forming a part of this specification, in which the figure is a plan view of a pillow-top, showing my design.

The design in its entirety consists of the 15 representation of a pair of dudishly-dressed persons, the figure of a groom carrying a cake appearing, following the pair, a banner appearing above the representation of the groom, and the persons appearing standing on a tile flooring within a border the top of which contains a scroll and open network, 20 the representation of the persons portraying the winners of a cake-walk.

The leading feature of the design consists of the representation of the persons portraying the winners of a cake-walk. 25

Having described my invention, what I claim as new, and desire to secure by Letters Patent, is—

The design for a pillow-top, as herein shown and described. 30

In testimony whereof I have signed my name to this specification in the presence of two subscribing witnesses.

RAFFAELLO ASTARITA.
